DESIGN FOR A DOG BED

Joseph J. Meyer, Milwaukee, Wis., assignor to G-H Specialty Company, Milwaukee, Wis., a corporation of Wisconsin

Application June 19, 1942, Serial No. 107,242

Term of patent 14 years

To all whom it may concern:

Be it known that I, Joseph J. Meyer, a citizen of the United States, residing at Milwaukee, in the county of Milwaukee and State of Wisconsin, have invented a new, original, and ornamental Design for a Dog Bed, of which the following is a specification, reference being had to the accompanying drawing, forming part thereof.

The figure in the drawing is a perspective view of the dog and bed, showing my design.

I claim:

The ornamental design for a dog bed, as shown.

JOSEPH J. MEYER.
